S. JOHNSON

FRICITION FIRE ESCAPE

Filed Dec. 6, 1922

UNITED STATES PATENT OFFICE.

SWAN JOHNSON, OF RICHWOOD, WEST VIRGINIA, ASSIGNOR OF ONE-HALF TO JULIA
ERLANDSON, OF RICHWOOD, WEST VIRGINIA.

FRICTION FIRE ESCAPE.

Application filed December 6, 1922. Serial No. 605,191.

To all whom it may concern:

- Be it known that I, SWAN JOHNSON, a citizen of Sweden, residing at Richwood, in the county of Nicholas and State of West Virginia, have invented certain new and useful Improvements in Friction Fire Escapes, of which the following is a specification, reference being had to the accompanying drawings.
10. This invention relates to fire escapes, and particularly to that class of fire escapes wherein a rope is frictionally engaged to prevent its paying out too quickly.
15. The general object of this invention is to provide a fire escape of this general character so constructed that it may be utilized by one person to gradually lower another person or which will permit one person to lower himself.
20. A further object is to provide a device of this character with very simple means whereby the passage of the rope around the drum of the fire escape may be readily and powerfully controlled.
25. A still further object is to provide a fire escape of this character including a drum around which a cable is wound, the drum being so constructed that the cable may pass around the drum any number of times de-
30. sired, and further to provide means whereby all of these windings of the cable may be engaged by the retarding device.

Another object is to provide means whereby the supporting hanger may be disposed in practically the same plane as one of the ends of the cable so that there will be no tendency of the drum and its corresponding parts to tip under strain.

Other objects will appear in the course 40 of the following description.

My invention is illustrated in the accompanying drawings, wherein:—

Figure 1 is a side elevation of my improved fire escape applied to permit one person lowering a second person;

Figure 2 is a like view to Figure 1, but illustrating the manner in which the fire escape is applied to permit a person to lower himself;

Figure 3 is a vertical sectional view through the drum when the latter is used under the circumstances illustrated in Figure 2;

Figure 4 is a section on the line 4—4 of 55 Figure 3;

Figure 5 is a top plan view of the drum illustrated in Figure 3;

Figure 6 is a fragmentary sectional view on the line 6—6 of Figure 4;

Figure 7 is a fragmentary front elevation 60 of the lower end of the construction shown in Figure 3;

Referring particularly to Figures 3 to 5, 10 designates a drum. This drum is not rotatable but is relatively fixed. The drum 65 is formed to provide two flanges 11, and passing through the drum and opening upon the periphery thereof are tubular rope ducts 12 and 13. It will be seen that both of these ducts extend out beyond the face of 70 the drum. The flanges of the drum may be cast or otherwise formed in one piece with the periphery of the drum or formed separately and attached thereto and the drum is formed at two points with inwardly projecting flanges 15 and the interior of the 75 drum may be solid except for the ducts 12 and 13. I have illustrated these ducts 12 and 13, however, as formed of tubular members inserted through the periphery of the 80 drum. These tubular members at their inner ends are formed with ears 16, and extending transversely, through the inwardly projecting flanges and through the ears 15 is a transverse pin 17. Mounted loosely 85 upon this pin are the two pulleys or grooved wheels 18. The periphery of the drum is formed with openings 19 into which these wheels 18 project, as illustrated most clearly 90 in Figure 4. It will be seen that the duct 12 opens adjacent one of the wheels 18 and the duct 13 opens adjacent the other wheel 18 and that these ducts are located adjacent opposite ends of the drum.

Swingingly connected to the transverse 95 pin or rod 17 are depending ears 20 connected by a transverse pin 21, and swingingly mounted upon this pin 21 is a yoke 22, the ends of the yoke being held in spaced relation by a sleeve 23. Swiveled in the 100 lower end of the yoke is a shackle 24 and swingingly engaged with this shackle is a hook 25 having a keeper 26. This hook 25 is adapted to be engaged with a supporting bracket A, as shown in Figure 1, or engaged 105 with a bolt or bolt holding member where the fire escape is arranged as in Figure 2. The cable or rope 27 is passed through one of the ducts as, for instance, through the duct 12, then passes a plurality of times 110

around the drum, then is passed through the other duct 13. When the drum is supported from the bracket A by means of the hook 25, both ends of the cable will extend downward, as shown in Figure 1. When, however, the fire escape is supported as in Figure 2, one end of the cable 27, which end is provided with a hook 28, will be engaged with the support A, while the other end of the cable beyond the fire escape will extend downward. While there will be some frictional engagement between the cable and the peripheral surface of the drum 10, this frictional engagement will not be sufficient to prevent a rapid descent of any one descending on the fire escape, and in order to provide for a variable frictional engagement of the cable I attach to the drum at one point the U-shaped yoke 29 which is held in place by a transverse rivet 30, as shown in Figure 4.

The flanges 11 of the drum are outwardly extended at 31 and radially slotted at 32 for the reception of the gudgeons 33 of a roller 34. The yoke 29 covers the slots 32 so that the roller 34 cannot get out of place. The yoke 29 is longitudinally slotted in its outer face at 35, and extending outward from this slot is a flange 36. Pivoted on this flange are crossed arms 37 having cam faces 38 which bear against the roller 34. The intersecting arms or shanks 37 are provided with handles 40 so formed that they may be readily grasped so as to draw the handles toward each other and thus force the cams 38 against the roller 34, forcing this roller inward against the convolutions of the cable 27 wrapped upon the drum. Preferably the outer convolutions of the cable are held or guided in place by inwardly extending lugs 41 which are bent inward from the flanges of the drum and then extend downward so as to arch over the two outer convolutions of the cable.

The operation of this device is as follows: Where it is necessary that one person should lower another, the person to be lowered is encircled by a belt or like device and this is hooked into the hook 28. The person controlling the fire escape then grasps the handles 40 and closes them to any degree required and thus applies friction to the rope and this will permit the cable to gradually descend. As a very great pressure may be applied to the cable and as this cable may be wrapped any desired number of times around the drum, it is obvious that the compression of the handles 40 will completely control the drum. If, however, there is one person to escape from the burning building, then it is only necessary to engage the hook 28 with the bracket A, to pass a rope or belt around the waist, and engage it with the hook 25. Then the person can clasp the handles 40 and by exerting more or less pres-

sure upon the handles 40 can permit himself to descend at any desired speed to the ground. Because of the very great pressure exerted upon the convolutions of the rope or cable, very great frictional engagement may be had with this rope or cable so that the paying out of the rope under any weight may be readily controlled.

Where the device is used as in Figure 2, it is desirable that the weight suspended from the hook 25 shall come as nearly as possible directly in line with the upper portion of the cable 27 and it is, therefore, desirable that the pivoted yoke 22 shall be shifted to that side of the drum adjacent the duct 13, and where the device is to be utilized, as shown in Figure 1, it is desirable, on the other hand, that the yoke 22 shall be shifted as nearly as possible into alignment with the duct 12. This is accomplished by forming this yoke 22 narrower than the length of the pin 21 so that it may slide on this pin and it is desirable, of course, to provide means whereby this yoke may be locked in its shifted position. To this end one end of the yoke 22 projects normally beyond the margin of flange 11 and is normally engaged between this flange 11 and the link 20. When it is desired to shift the yoke, the yoke is turned so as to bring its arms into tangential relation to the flange 11, then the yoke is shifted to the opposite end of the pin 21, and again turned into radial position, which will bring one of the arms of the yoke outside of the flange 11. This locks the yoke in either of its two positions so that thereafter in the use of the device the yoke will remain adjacent to and nearly in alignment with that end of the cable or rope which is supporting the weight.

It will be seen that this device is very simple, may be cheaply made, and is thoroughly effective in practice. I do not wish to be limited to the details of construction, as these may be varied in many ways without departing from the spirit of the invention as defined in the appended claims.

I claim:—

1. In a fire escape, a drum having end flanges and formed to provide ducts extending inward from opposite surfaces of the drum, pulleys disposed at the inner ends of the ducts, a cable passing around the periphery of the drum and passing through said ducts and over said pulleys, a shackle operatively connected to the drum, and manually operable means mounted on the drum for frictionally engaging the cable with the drum.

2. In a fire escape, a drum having end flanges and formed to provide ducts extending inward from opposite surfaces of the drum, a cable passing around the drum and passing through said ducts, a shackle operatively connected to the drum, and manu-

- ally operable means mounted on the drum for frictionally engaging the cable with the drum comprising a roller extending parallel to the surface of the drum and mounted for movement toward the surface of the drum, and a manually operable cam engaged with said roller.
3. In a fire escape, a drum having end flanges and formed to provide ducts extending inward from opposite surfaces of the drum, a cable passing around the drum and passing through said ducts, a shackle operatively connected to the drum, means for frictionally engaging the cable with the drum comprising a roller extending parallel to the surface of the drum and mounted for movement toward the surface of the drum, and a pair of cams engaging said roller, said cams having shanks crossing each other, the shanks having handles whereby the cams may be forced to engage the roller and force the roller against the cable.
4. In a fire escape, a drum having flanges at its opposite ends, a yoke pivotally engaging said flanges and carrying a supporting hook, the drum being formed with cable ducts each extending at one end through the periphery of the drum and each duct opening at its other end within the drum and in spaced relation to the periphery thereof, the cable extending around the drum a number of times and having its ends passed through said ducts, and means for frictionally engaging the cable comprising a yoke mounted upon the drum, a roller mounted in said last-mentioned yoke and movable toward or from the face of the drum, and manually operable means mounted upon the last-mentioned yoke for urging said roller toward the face of the drum and against the convolutions of the cable.
5. A fire escape comprising a drum formed with flanges, grooved rollers mounted upon the inner face of the drum and adjacent each end thereof, the periphery of the drum having openings into which said rollers project and the drum being formed to provide ducts opening adjacent said rollers at one end and extending through the face of the drum at the other and projecting slightly beyond the face of the drum, a cable passing through said ducts and extending around the drum a number of times and bearing upon said grooved rollers, one end of the cable being provided with an attaching device, a yoke mounted upon the drum, a roller mounted in said yoke and extending parallel to the outer face of the drum, manually operable means for forcing said roller toward the face of the drum and against the cable wrapped thereon, links pivoted to the drum, a pin connecting the outer ends of said links and extending parallel to the face of the drum, the links being disposed adjacent said rollers, and a yoke mounted upon said pin and having a hook.
6. A fire escape comprising a drum formed with flanges, grooved rollers mounted upon the inner face of the drum and adjacent each end thereof, the periphery of the drum having openings into which said rollers project and the drum being formed to provide ducts opening adjacent said rollers at one end and extending through the face of the drum at the other and projecting slightly beyond the face of the drum, a cable passing through said ducts and extending around the drum a number of times and bearing upon said grooved rollers, one end of the cable being provided with an attaching device, a yoke mounted upon the drum, a roller mounted in said yoke and extending parallel to the outer face of the drum, manually operable means for forcing said roller toward the face of the drum and against the cable wrapped thereon, links pivoted to the drum, a pin connecting the outer ends of said links and extending parallel to the face of the drum, the links being disposed adjacent said rollers, and a yoke mounted upon said pin and having a hook.
7. A fire escape comprising a drum formed with flanges, grooved rollers mounted upon the inner face of the drum and adjacent each end thereof, the periphery of the drum having openings into which said rollers project and the drum being formed to provide ducts opening adjacent said rollers at one end and extending through the face of the drum at the other and projecting slightly beyond the face of the drum, a cable passing through said ducts and extending around the drum a number of times and bearing upon said grooved rollers, one end of the cable being provided with an attaching device, manually operable means for frictionally engaging the cable with the drum, links pivoted to the drum, a pin connecting the outer ends of said links and extending parallel to the face of the drum, the links being disposed adjacent said rollers, and a yoke mounted upon said pin and having a hook, said yoke being shiftable upon the pin from one end of the drum to the other and having means whereby it may be locked in shifted position.
8. In a fire escape, a drum having end flanges, a cable passing around the drum, supporting means operatively connected to

1
the drum, means for frictionally engaging the cable with the drum comprising a roller extending parallel to the surface of the drum and mounted for movement toward
5 the surface of the drum, and a pair of cams engaging said roller, said cams having shanks crossing each other, the shanks having handles whereby the cams may be forced to engage the roller and force the
10 roller against the cable.

9. In a fire escape, a drum having end flanges and formed to provide two parallel ducts extending inward from adjacent points on the periphery of the drum, said
15 ducts being laterally spaced from each other, a cable passing around the drum and passing through said ducts, manually oper-

able means for frictionally engaging the cable with the drum, ears extending downward from the drum, a supporting rod extending parallel to the axis of the drum, a shackle slidably mounted upon said rod, the rod being disposed at a point approximately diametrically opposite to the outer ends of the ducts, the shackle being movable transversely of the drum on said rod into a position approximately in line with either one of said ducts, and means for locking the shackle in this position from lateral movement.
